DESIGN FOR A SCYTHE

George W. Carlson, Minneapolis, Minn.

Application September 4, 1945, Serial No. 121,830

Term of patent 14 years

(Cl. D35—2)

To all whom it may concern:

Be it known that I, George W. Carlson, a citizen of the United States, in the county of Hennepin and State of Minnesota, have invented a new, original, and ornamental Design for a Scythe, of which the following is a specification, reference being had to the accompanying drawing, forming part thereof.

Fig. 1 is an elevational view of a scythe in operative position and showing my new design;

Fig. 2 is a plan view of the scythe, as shown in Fig. 1;

Figs. 3, 4 and 5 are sectional views taken on the lines 3—3, 4—4 and 5—5 of Fig. 1, respectively, on an enlarged scale.

I claim:

The ornamental design for a scythe, as shown.

GEORGE W. CARLSON.
